UNITED STATES PATENT OFFICE.

MARCUS MASHBIR, OF NEW YORK, N. Y.

SEWING-MACHINE FINGER-GUARD.

1,000,740.

Specification of Letters Patent. Patented Aug. 15, 1911.

Application filed June 22, 1909. Serial No. 503,653.

To all whom it may concern:

Be it known that I, MARCUS MASHBIR, a citizen of the United States, and a resident of New York, borough of Brooklyn, county 5 of Kings, and State of New York, have invented certain new and useful Improvements in Sewing-Machine Finger-Guards, of which the following is a full, clear, and exact description.

10 This invention relates more particularly to a finger guard to prevent injury to the operator's fingers by the machine needle or needles.

15 The primary object of the invention is to provide a simple and efficient device or attachment adapted to be operatively connected to the presser foot or presser foot bar of a sewing machine in such a way that the fingers of the operator cannot possibly come 20 in contact with the needle or needles of the machine as the same is operated, and at the same time permit the movements of the needle to be seen in order that the quality of the stitch and the straightness of the seam 25 may be carefully watched.

30 A further object of the invention is to provide a device which is adapted for use in connection with various forms of sewing machines employing one or a number of needles.

35 With these and other objects in view, the invention will be hereinafter more particularly described with reference to the accompanying drawings, which form a part of this specification, and will then be pointed out in the claims at the end of the description.

40 In the drawings, Figure 1 is a perspective view of one form of device embodying my invention. Fig. 2 is a fragmentary plan view of the presser foot. Fig. 3 shows a slightly different means for holding the device to the presser foot bar.

45 The machine head 10 may be provided with the usual form of presser foot bar 11 on the lower end of which is held the presser foot 12 having the usual slot and opening, as 13, for the reciprocatory movement of the needle 14, and said needle is held to 50 the needle bar 15, all of which may be of the usual or of any preferred construction and operated in any desired way.

55 The device or guard 16 is provided with a substantially U-shaped body 17 one leg of which has its end, as 18, held in a slot 19 in the presser foot, and secured to or formed

as a part of the body 16 in an arm 19^a, one end of which, as 20, is arranged at an angle to the fastening part 21 so as to hold the body 16 properly and adjacent to the needle 60 14, and said arm 19^a is provided with a slot 22 through which a screw 23 passes to permit adjustment of said arm. A screw 23 passes through the slot 22 and is held to the end of a bar 24, and this bar is supported 65 in a clip or bracket 25 which is held to the bar 11 by a screw 26 or otherwise. As thus constructed the guard or device is movable with the presser foot and bar and may be adjusted relatively to the foot, though it 70 will be understood that the end 18 of the guard need not be made to fit into a slot or be otherwise held to the presser foot if desired.

75 In case the guard is intended for use in connection with a machine having a single needle, the body part 16 may have its legs close enough together to prevent the fingers of the operator from passing through the slot between the legs of the body, but in 80 case the machine employs a number of needles, as is sometimes the case, the legs will thus be placed farther apart, and to prevent the fingers from entering the space between the legs is a glass or other plate 27. 85 This plate 27 may be of any suitable transparent material and is held to the body 16 in any desired way and will permit the working of the needle and the quality of the 90 stitches and the straightness of the seam being made to be readily seen.

95 In Fig. 3 the guard is entirely independent of the presser foot otherwise the guard and its supporting arm is substantially the same as in Fig. 1. In this construction the arm 19^a has the slot 22 by which the guard may be adjusted and has a screw 28 passing through the slot, and said screw engages a bar or post 29 extending outward from a sleeve 30 which fits about the 100 presser foot bar 11, the said sleeve being secured to said bar by means of a screw 31.

105 From the foregoing it will be seen that a simple and efficient guard is provided which will protect the hands of the operator and at the same time permit the quality of the stitches and the nature of the seam to be readily seen at all times; that said guard may be variously constructed and held and may be movable with the presser foot; and that said guard is adapted for use in connection with various forms of machines, and 110

may be made so that it can be used where a single needle is employed or where the machine uses a number of needles.

Having thus described my invention, I claim as new and desire to secure by Letters Patent:

1. The combination with a needle, of a presser foot, a guard secured thereto and movable with the presser foot and having a substantially U-shaped body, a transparent plate held to said body, an angular arm supporting the body of the guard, said arm being provided with a slot, an arm, means for holding the arm to the presser foot bar, and a screw passing through the slot of the arm and engaging the bar to hold the guard in an adjusted position.
2. A sewing machine finger guard having a substantially U-shaped body, a transparent plate held to said body, an angular arm supporting the upper end of the body of the guard, said arm being provided with a slot, a bar, and means for holding the arm to the bar.
3. In a sewing machine finger guard, a substantially U-shaped body adapted to be vertically disposed in front of the needle and upon the presser foot of the sewing machine, an arm having at one end an angular part integral with the upper part of the U-shaped body, and provided with a slot at the other end thereof, a bar adapted to be adjustably held to the presser foot bar

of the sewing machine, and a screw passing through the slot and engaging said arm.

4. A sewing machine finger guard of the character described, comprising a substantially U-shaped body vertically disposed in front of the machine needle and adapted to be movable with the presser foot bar of the machine, and means independently of the presser foot for connecting said body to the presser foot bar.

5. The combination with the presser foot held upon the presser foot bar of a sewing machine, of a finger guard comprising a substantially U-shaped body vertically disposed above the free end of the presser foot and in front of the machine needle, an arm directed at an angle with respect to the U-shaped body and having at one end an angular part formed upon the upper edge of the body, a slot provided in the opposite end of the arm, a bar adapted to be adjustable along the presser-foot bar, means to hold one end of the bar in an adjusted position to the presser foot bar, and means adapted to adjustably hold the arm to the opposite end of said bar.

This specification signed and witnessed 60 this 19th day of June A. D. 1909.

MARCUS MASHBIR.
